UNITED STATES PATENT OFFICE.

H. HERMAN WESTINGHOUSE, OF PITTSBURG, PENNSYLVANIA, ASSIGNOR TO
THE WESTINGHOUSE MACHINE COMPANY, OF SAME PLACE.

STEAM-ENGINE.

SPECIFICATION forming part of Letters Patent No. 340,022, dated April 13, 1886.

Application filed January 18, 1886. Serial No. 188,832. (No model.)

To all whom it may concern:

Be it known that I, H. HERMAN WESTINGHOUSE, residing at Pittsburg, in the county of Allegheny and State of Pennsylvania, a citizen of the United States, have invented or discovered certain new and useful Improvements in Steam-Engines, of which improvements the following is a specification.

In the accompanying drawings, which make part of this specification, Figure 1 is a vertical longitudinal section taken through the centers of the cylinders of an engine embodying my invention, and Fig. 2 a vertical transverse section at the center of the low-pressure cylinder.

My invention relates to improvements in single-acting steam-engines, more particularly those of the class in which two or more cylinders are connected to and open at one end into a closed crank case or chamber, within which a crank-shaft, to the cranks of which the pistons of the cylinders are coupled, is adapted to rotate in a bath of lubricating-liquid, as is exemplified in Reissued Letters Patent No. 10,603, granted and issued to The Westinghouse Machine Company, as my assignee, May 26, 1885.

The object of my present invention is to provide in a single-acting engine means for properly cushioning the downward stroke of the piston and imparting an initial upward tendency thereto, and for maintaining the piston in proper relation to its crank by the exertion of a suitable retarding action upon the piston toward the terminal of its upward stroke; also to provide in a compound single-acting engine embodying the characteristic features of the type above indicated, as is instanced in my application Serial No. 174,878, filed August 20, 1885, suitable means for preventing the ejection of lubricating material from the crank-case by reason of unequal displacement of the pistons.

To these ends my invention, generally stated, consists in a single-acting cylinder having a closed internal cushion-chamber on the side of its piston opposite that which receives steam-pressure, and in the combination of a high-pressure single-acting cylinder and a low-pressure single-acting cylinder of larger diameter, each located above a closed crank-case adapted to contain lubricating material, and having pistons connected to cranks on a

shaft therein, a trunk or tubular extension fixed to the low-pressure piston and corresponding in diameter with the high-pressure piston, and a head closing the inner end of the low-pressure cylinder and provided with a sleeve or casing inclosing the trunk of the low-pressure piston.

The improvement claimed is hereinafter fully set forth.

My invention is herein exemplified as applied in a compound single-acting engine, the general structural features of which correspond, substantially, with those of the engine set forth in my application Serial No. 174,878, before referred to, sundry of which, being either heretofore patented or constituting part of the subject-matter of said application, are not herein claimed. A high-pressure cylinder, 1, and a low-pressure cylinder, 2, of larger diameter, between which is interposed a valve chest or chamber, 3, are secured upon the top of a closed crank-case, 5, which constitutes the bed or support of the engine, and likewise serves as a tank or receptacle for the lubricating material of the crank-shaft journals and crank-pins, the same being preferably a mixture of oil and water, which, by the rotation of the shaft and cranks, is in the operation of the engine constantly sprayed over the parts to be lubricated. Access to the interior of the crank-case is afforded, as desired, by a removable bonnet, 6, secured to one side of the crank-case over an opening therein.

The high and low pressure cylinders 1 2 are fitted, respectively, with pistons 7 8, which are coupled by connecting-rods 9 9 to crank-pins set oppositely or at angle of one hundred and eighty degrees upon a pair of double cranks, 10 10, formed upon a crank-shaft, 4, having journals mounted in bearings in the ends of the crank-case 5, and carrying one or more balance-wheels, 42, and a belt-pulley, 43. Steam is supplied to the valve-chamber 3 from the boiler by a steam-pipe secured to a flange or nozzle on the side of the valve-chamber, and is admitted to and exhausted from the upper ends of the high and low pressure cylinders 1 2 by a main or distribution valve, 12, which is coupled to an eccentric-rod, 19, secured to the strap 20 of an eccentric mounted on the crank-shaft 4, said eccentric being preferably adapted to be

moved transversely to the crank-line, so as to vary the travel of the valve in correspondence with variations of pressure or resistance, or both, by a suitable centrifugal governor connected to and rotating with a disk or carrier, 25, fixed upon the crank shaft. The distribution-valve 12 primarily admits steam from the valve-chamber to the space above the high-pressure piston 7 through a port, 74, thereafter exhausts the steam, which has effected the downward stroke of said piston, through the port 74, the tubular body of the valve, and a port, 14, into the space above the low-pressure piston 8, and finally exhausts said steam, after it has effected the downward stroke of the low-pressure piston, through the port 14 and through exhaust-ports 70 in the valve to an exhaust-pipe leading to a condenser or to the atmosphere.

20 The operation of an engine as above described has failed to be wholly satisfactory in practice, when the lower ends of both the high and low pressure cylinders are open to the crank-case, by reason of the fact that the unequal displacements of the larger and smaller pistons 7 and 8 in their traverse act to force the lubricating material out of the crank-case, and, further, by reason of the absence of means for properly cushioning the low-pressure piston at the lower terminal of its stroke and maintaining its due relation to its crank-pin at its upper terminal. These objections are fully and satisfactorily obviated by the following construction: The lower end of the high-pressure cylinder 1 is left wholly open to the crank-case, and the lower end of the low-pressure cylinder 2 is closed by a tight head, 15, having a central cylindrical sleeve or casing, 16, which incloses a trunk or cylindrical projection, 17, formed upon or secured to the lower side of the low-pressure piston 8 and corresponding in diameter with the high-pressure piston 7, said trunk carrying the pin to which the upper end of the connecting-rod 9 of the low-pressure piston is coupled.

25 The trunk 17 and sleeve 16 are made of such length that a portion of the trunk shall be inclosed by the sleeve at all points of the stroke of the piston 8, or, in other words, that the space or cushion-chamber 18 around the trunk and between the lower side of the piston 8 and the head 15 shall be at all times closed to the crank-case, such space being obviously equally closed to the steam-space above the piston. It will therefore be seen that as the displacement of the low-pressure piston-trunk 17 is equal to that of the high-pressure piston 7 the lubricating-material in the crank-case will be undisturbed by the movements of said members, and that the air entrapped within the cushion-chamber 18 will be compressed therein during the lower half of the downward stroke of the low-pressure piston 8, thereby cushioning said piston at its lower terminal and imparting to it an initial impetus for its suc-

ceeding upward stroke. During the upper half of the upward stroke of the low-pressure piston the retarding influence of the air in the cushion-space under the exhausting action of said piston acts to cushion the piston at its upper terminal and maintain its normal connected relation to its crank-pin in tending to effect its downward stroke.

75 For the purpose of relieving any excess of pressure in the cushion-chamber 18 and admitting of the discharge of water of condensation due to leakage of steam thereinto, the cushion-chamber is provided with a check or relief valve, 21, which opens outwardly, and is loaded by a spring or weight in accordance with the pressure proper to be maintained in the chamber.

I claim herein as my invention—

80 1. In a single-acting compound engine, the combination of a crank-case, a high pressure cylinder and a low-pressure cylinder of larger diameter connected to said crank-case, and pistons fitting said cylinders and open to the crank-case through surfaces of equal area on their sides adjacent thereto, substantially as set forth.

85 2. In a single acting compound engine, the combination of a crank-case, a high-pressure cylinder and a low-pressure cylinder of larger diameter connected to said crank-case, a trunk fixed to the low-pressure piston on the side adjacent to the crank-case and corresponding in diameter with the high-pressure piston, and a head closing the crank-case end of the low-pressure cylinder, and provided with a sleeve or easing inclosing the trunk of its piston, substantially as set forth.

90 3. In a single-acting engine, a cylinder having a closed internal cushion-chamber on the side of its piston opposite to that which receives steam pressure, substantially as set forth.

95 4. In a single-acting engine, the combination of a cylinder and a piston working therein and having a trunk on its side opposite that which receives steam-pressure, said trunk passing through a head in the adjacent end of the cylinder and forming with the piston a closed cushion-chamber therein, substantially as set forth.

100 5. In a single-acting engine, the combination of a cylinder, a piston working therein and having a trunk on its side opposite that which receives steam-pressure, said trunk passing through a head in the adjacent end of the cylinder and forming with the piston a closed cushion-chamber therein, and a check or relief valve controlling a passage leading out of said cushion-chamber, substantially as set forth.

105 In testimony whereof I have hereunto set my hand.

H. HERMAN WESTINGHOUSE.
